(57) **CLAIM**

The ornamental design for a press mold set for fork as shown and described.

DESCRIPTION

FIG. 1 is a perspective view of the press mold set for fork showing a top layer press mold and a bottom layer press mold thereof;

FIG. 2 is a top perspective view of the press mold set for fork showing the top layer press mold; shown separately for ease of illustration;

FIG. 3 is a bottom perspective view as shown in FIG. 2;

FIG. 4 is a front elevational view as shown in FIG. 2;

FIG. 5 is a rear elevational view as shown in FIG. 2;

FIG. 6 is a left side elevational view as shown in FIG. 2;

FIG. 7 is a right side elevational view as shown in FIG. 2;

FIG. 8 is a top plan view as shown in FIG. 2;

FIG. 9 is a bottom plan view as shown in FIG. 2;

FIG. 10 is a top perspective view of the bottom layer press mold; shown separately for ease of illustration;

FIG. 11 is a bottom perspective view as shown in FIG. 10;

FIG. 12 is a front elevational view as shown in FIG. 10;

FIG. 13 is a rear elevational view as shown in FIG. 10;

FIG. 14 is a left side elevational view as shown in FIG. 10;

FIG. 15 is a right side elevational view as shown in FIG. 10;

FIG. 16 is a top plan view as shown in FIG. 10;

FIG. 17 is a bottom plan view as shown in FIG. 10; and,

FIG. 18 is a reduced-scale perspective view thereof, showing the top layer press mold and the bottom layer press mold separately.

The broken lines shown in the figures depict portions of the press mold set for fork that form no part of the claimed design.
